(57) **CLAIM**

The ornamental design for a positionable lanyard ring for a mobile computer device, as shown and described in FIGS. 1-16.

DESCRIPTION

FIG. 1 is a front view of a positionable lanyard ring for a mobile computer device;

FIG. 2 is a rear view of the positionable lanyard ring for a mobile computer device from FIG. 1;

FIG. 3 is a side exploded view of the positionable lanyard ring for a mobile computer device from FIG. 1, depicting the detachable lanyard ring between the mobile device and battery cover;

FIG. 4 is an opposite side exploded view of the positionable lanyard ring for a mobile computer device from FIG. 1, depicting the detachable lanyard ring between the mobile device and battery cover;

FIG. 5 is top exploded view of the positionable lanyard ring for a mobile computer device from FIG. 1, depicting the detachable lanyard ring between the mobile device and battery cover;

FIG. 6 is a bottom exploded view of the positionable lanyard ring for a mobile computer device from FIG. 1, depicting the detachable lanyard ring between the mobile device and battery cover; and

FIG. 7 is a perspective exploded view of the positionable lanyard ring for a mobile computer device from FIG. 1, depicting the detachable lanyard ring between the mobile device and battery cover.

FIG. 8 is a front view of a positionable lanyard ring for a mobile computer device with the lanyard oriented in the lower left position;

FIG. 9 is a rear view of a positionable lanyard ring for a mobile computer device of FIG. 8;

FIG. 10 is a side view of a positionable lanyard ring for a mobile computer device of FIG. 8;

FIG. 11 is an alternate side view of a positionable lanyard ring for a mobile computer device of FIG. 8;

FIG. 12 is a top view of a positionable lanyard ring for a mobile computer device of FIG. 8;

FIG. 13 is a bottom view of a positionable lanyard ring for a mobile computer device of FIG. 8;

FIG. 14 is a perspective view of a positionable lanyard ring for a mobile computer device of FIG. 8;

FIG. 15 is a perspective view of the positionable lanyard ring for a mobile computer device of FIG. 8; and,

FIG. 16 is an alternate perspective view of the positionable lanyard ring for a mobile computer device of FIG. 8.

The broken lines illustrate environment that forms no part of the claimed design.

In some embodiments, line shading is meant to show contour of represented surfaces and not surface ornamentation.
